SPRAYER

William Martin Vogel, Montclair, N. J.

Application November 1, 1945, Serial No. 625,970

4 Claims. (Cl. 21—78)

1

This invention relates to spraying devices, and more particularly to those employed for spraying insecticides, disinfectants, deodorants and the like into clothing closets, wardrobe cabinets, chests and other closed containers.

At the present time, when an effort is made to spray a liquid disinfectant, insecticide or deodorant into a clothing closet, wardrobe or other container, and particularly those in which clothing is contained, the door to the closet or other container is usually left open while the spraying operation takes place so that a great deal of the sprayed liquid, which is usually in the form of a fine mist or spray, is dissipated and lost outside of the container or chamber for which it was intended.

The present invention contemplates the provision of a spraying device adapted for attachment to a cabinet, wardrobe, chest or similar container, and by means of which the interior of the container and consequently the contents thereof, may be sprayed while the door or other closure for the container is closed. The result of the use of such a construction is that the spray, emitted within the container will be retained therein, will not readily reach the outside atmosphere and the effect of the sprayed substance on the contents of the chamber will be materially amplified.

More particularly, the invention resides in the provision of means for supporting a receptacle containing the material to be sprayed, within the chamber or compartment; of the provision of an air spray tube extending through one of the walls or other parts of the chamber and having one end disposed inside of the chamber and its other end outside of the same, the latter end being adapted to receive an air pump or other air-pressure creating means by which blasts of air may be directed through the air spray tube and cause the material to be sprayed inside of the chamber, said spraying operation taking place while the door or other closure means for the chamber remains closed.

These and other objects are accomplished by the invention, a more particular description of which will hereinafter appear and be set forth in the claims appended hereto.

In the accompanying drawing, wherein an illustrative embodiment of the invention is disclosed, Fig. 1 is a sectional view, showing the improved spraying device as applied to the wall or other part of a cabinet, wardrobe, or the like; Fig. 2 is a side view of the air blast tube, with the cap of the receptacle and the feed tube

2

extending therethrough, being shown in section; Fig. 3 is a sectional view on the line 3—3 of Fig. 2, looking in the direction of the arrows, and Fig. 4 is an end view of the structure of Fig. 4, looking at the left end of the same.

With reference to Fig. 1 of the drawing, a portion of a cabinet, clothing wardrobe or other container or chamber in which it is desired to spray insecticide, disinfectant, deodorant or the like, is indicated at 1. A wall of the cabinet is indicated at 2, the same being provided with an aperture 3 extending through it to permit the passage of an air tube or nozzle 5. The outlet end of the tube or nozzle 5 is located on the interior of the cabinet 1 and in the form shown, the same is provided with a threaded cap member 9 to which is detachably secured the receptacle 11 containing the disinfectant, insecticide or other preparation to be sprayed within the interior of the cabinet. A feed tube 10 extends through the cap 9 to reach the interior of the receptacle 11 and the contents of the same.

The shank of the air tube 5 is threaded for the greater portion of its length and it is held in place through the aperture 3 in the wall 1 of the cabinet by means of the nuts 6 and 7 disposed on the opposite sides of the wall 2. This arrangement is such as to provide a nipple portion 12 beyond the nut 7 on the outside of the cabinet, said portion being threaded to permit of the detachable securing of the end 13 of a hand pump 14. Said pump may be of the conventional type employed on sprayers, and includes the cylinder 15 containing a piston 16 connected to the rod 17 terminating in the handle 18 located outside of the cylinder. This construction enables the pump 14 to be readily attached to the end portion or nipple 12 of the tube 5 whenever desired and by operation of the pump the interior of the cabinet will be sprayed with the contents of the receptacle 11. Since the spraying operation is carried out by the air being directed through the tube 5, and since the outlet end of the air nozzle and spray tube 10 are located within the cabinet, it will be obvious that the door or other closure for the cabinet need not be opened to permit the spraying operation to take place. Hence, it will be clear that the preparation sprayed within the cabinet cannot escape readily and will be retained within the cabinet for a greatly increased period of time, thus greatly increasing the effectiveness of the sprayed preparation.

While the spraying elements disposed within

the cabinet are shown as projecting from a flat wall thereof, it will be clear that they may be otherwise located so as not to encroach upon the containing area or storage space in the cabinet. For example, the spray nozzle and the receptacle 11 maintained thereby, might be located in a corner of the cabinet or at any other convenient location.

The passage 19 through the air tube 5 is relatively small in diameter and therefore the escape therethrough of the sprayed preparation is very slow. However, even this slight escape of the sprayed material can be prevented if desired, if the nipple portion 12 on the outside of the cabinet is capped by a thread-on cap as soon as the pump 14 is detached at the end of the spraying operation. A valve might also be provided by means of which the passage 19 could be closed upon the detachment of the pump 14, thereby confining the sprayed preparation within the cabinet.

In use of the device, the cabinet can be packed with the garments or other articles, and the door or other closure for the cabinet can then be closed or even sealed. The pump is then attached by threading the nozzle portion 13 onto the threaded end 12 of the air tube 5, and the pump is operated externally of the cabinet to the extent required to thoroughly spray the interior of the closed cabinet. At the completion of the spraying operation, the pump is detached and if desired, the passage 19 closed by a thread-on closure cap applied to the end 12 of the tube 5 if a complete closure of the cabinet is desired. From time to time, as the occasion requires it, the interior of the cabinet can be sprayed, each time the operation being performed as above described and without requiring the opening of the cabinet, this not being required until it is desired to remove the contents of the cabinet or until the contents of the receptacle 11 are depleted.

While I have herein shown a certain way of securing the air tube in place, and have shown said tube and associated parts of a certain design, wherein the tube is contracted as at 4 and has a narrowed portion 8 to which the cap 9 is attached, a different form of spraying means might well be used and the same might be otherwise attached to the cabinet. The primary result sought is the provision of means by which a cabinet or other closed container can be effectively sprayed exteriorly of the container thus confining the sprayed preparation within the container, and this attained by the structure disclosed and set forth in the claims appended hereto.

What I claim is:

1. In a sprayer attachment for cabinets, chests or other closed containers, the container having a fixed wall provided with a tubular passage extending through it and having one end commu-

nicating with the exterior of the container, a liquid container located within the cabinet and having a spray tube located at the inner end of the passage whereby air delivered through the latter will spray the liquid throughout the interior of the cabinet, the second end of the passage being located on the outside of the cabinet and having means for detachably receiving and supporting a hand-operated air pump and permitting hand operation of the pump and spraying inside of the cabinet without requiring opening of the door thereof.

2. A sprayer attachment for spraying the inside of a closed cabinet provided with a fixed cabinet wall comprising, a tube passing through said wall, a liquid-holding spray receptacle contained within the cabinet and supported therein adjacent to the inner end of the tube, the tube having an outer end located on the outside of the cabinet, a hand-operated air pump provided with coupling means by which it is coupled to and supported by the outer end of said tube, said pump when so coupled to the tube being capable of operation to thereby spray the interior of the cabinet while the cabinet is in a fully closed condition.

3. A sprayer for closed cabinets and the like having a wall, an air tube mounted in the wall and having its outlet end located within the cabinet, said tube being connected to a liquid-holding container also located within the cabinet, the air tube passing through the wall of the cabinet and being provided with means located on the outside of the cabinet for coupling it to a pump for the forcing of air by said pump through said tube while the cabinet is completely closed and by operation of said pump on the outside of the closed cabinet.

4. A sprayer as provided for in claim 3, wherein in the air tube is a threaded element and is held by nuts in the wall of the cabinet, and the air tube has a threaded portion on the outside of the cabinet, and the pump is threadably attached to said threaded portion on the outside of the cabinet.
